US00D950746S

(12) **United States Design Patent** (10) **Patent No.:** **US D950,746 S**
Baltazar (45) **Date of Patent:** **** May 3, 2022**

(54) **TEMPERATURE THERAPY APPARATUS**(71) Applicant: **Biofreeze IP Holdings, LLC**, Akron, OH (US)(72) Inventor: **Carol Baltazar**, Glenwood, MD (US)(73) Assignee: **TheraPearl, LLC**, Columbia, MD (US)(***) Term: **15 Years**(21) Appl. No.: **29/740,216**(22) Filed: **Jul. 1, 2020****Related U.S. Application Data**

(60) Continuation-in-part of application No. 29/644,303, filed on Apr. 17, 2018, now Pat. No. Des. 904,633, which is a continuation-in-part of application No. 29/558,760, filed on Mar. 21, 2016, now abandoned, which is a continuation of application No. 29/498,786, filed on Aug. 7, 2014, now Pat. No. Des. 787,082, which is a continuation-in-part of application No. 29/429,157, filed on Aug. 7, 2012, now abandoned, which is a division of application No. 12/794,576, filed on Jun. 4, 2010, now abandoned.

(51) **LOC (13) Cl.** ..... **24-04**(52) **U.S. Cl.**USPC ..... **D24/206**(58) **Field of Classification Search**

USPC ..... D24/206-208, 189-192, 118; 602/1-7, 602/17-27, 61-66, 74, 30; 128/112.1, 128/117.1, 95.1, 96.1, 97.1, 100.1, 101.1, 128/876; 606/204, 27; 604/96, 108, 109, 604/111, 112; D29/121.2, 122, 101.2, D29/101.5, 120.1, 121.1, 108; D3/327; D9/707; 601/15, DIG. 1; 126/204

CPC .. A47G 9/1036; A61F 7/10; A61F 2007/0002

(57) CLAIM

The ornamental design for a temperature therapy apparatus, as substantially shown and described.

DESCRIPTION

The FIGURE is a top, two-dimensional, plan view of a temperature therapy apparatus showing the new design.

1 Claim, 1 Drawing Sheet# US D950,746 S
